AMPLIFYING DEVICE

Arthur Bessey Smith, Evanston, Ill., assignor to
 Automatic Electric Laboratories, Inc., Chicago,
 Ill., a corporation of Delaware

Application August 20, 1943, Serial No. 499,357

7 Claims. (Cl. 179—171)

1

This invention relates to improvements in amplifying devices and its purpose is to provide an improved electrically operated mechanical amplifier of audible frequencies adapted for use in telephone systems, loud speaker systems and the like where it is desirable to amplify the vibrations produced by telephone speech.

In a device of this type, an armature is mounted to vibrate between the pole faces of a polarized electromagnet and is operatively connected to the electrodes of microphone cells. The alternating current to be amplified energizes the coils of the electromagnet and vibrates the armature, thereby actuating the electrodes of the microphone cells and producing undulations in a connected direct current circuit which includes an induction coil or transformer for sending out oscillations of increased power or amplitude.

In an amplifier of this type, as heretofore generally constructed, the armature, which is ordinarily pivotally mounted, is in unstable equilibrium in its central or neutral position and tends to snap powerfully to either extreme position due to the action of the polarized magnet. For a limited movement in either direction from this neutral position, the armature is attracted by a magnetic force which is "linear," that is, it increases in a uniform manner as the pole faces are approached, but as the end portions of the armature approach very closely to the pole faces the magnetic force increases very rapidly, thus producing irregularity and instability in armature action.

The principal object of the present invention is to overcome the above-mentioned difficulties, in an improved manner, by providing an amplifying device of the type referred to in which the magnetic torque due to the polarization of the magnetizable core is substantially neutralized so that the armature tends to remain in any position to which it is moved and is thus in a stable position at all times within its field of vibration. This is preferably accomplished by the use of a spring or other equivalent device which opposes the movement of the armature from its central or neutral position and which tends to return it to that position. By this means, the present invention tends to prevent any tuning of the vibrations of the armature for any particular frequency in the receiving circuit and insures the desired uniformity of operation.

An important feature of the invention is the provision in an amplifier of the type referred to of means for confining the vibrations of the armature substantially to the range in which the

2

magnetic attraction increases uniformly as the pole faces are approached. This object may preferably be attained by providing the pole faces with coatings of non-metallic material such as paper, yarn or the like which may be applied in any desired thickness and which not only confine the armature to the desired range of movement during its normal operation but also prevent the sticking of the armature to the pole faces when starting.

A further object is to provide an improved microphone cell which may be used in an amplifier circuit or other circuit for setting up oscillations in response to movements of a connected vibrating armature or the like. In its preferred form this microphone cell comprises a chamber containing carbon granules and connected with the armature or other actuating member by a flexible non-metallic member, which may be a tubular collapsible member forming a continuation of said chamber and containing some of said carbon granules which are held thereby in contact with the actuating member. The armature or other actuating member is preferably provided with a non-magnetic contact plate which directly engages the carbon granules and this contact plate and the interior surfaces of said chamber are preferably plated with gold or the like to improve the microphonic action.

30 These and other objects of the invention will be more fully understood from the following specification taken with the accompanying drawings in which one embodiment is illustrated. In the drawings,

35 Figure 1 shows a side elevation of one form of the improved amplifier of the present invention;

Fig. 2 shows a horizontal section through the improved amplifier of the present invention, the section being taken on the line 2—2 of Fig. 1;

40 Fig. 3 is a diagram showing the balancing effect of the polarized magnet and the resilient mounting of the armature within the working range of movement of the armature;

Fig. 4 shows an end elevation of the structure 45 illustrated in Fig. 1, looking toward the left as viewed in Fig. 1;

Fig. 5 shows a perspective view of the front half of the winding shell or spool, which is embodied in the structure illustrated in Figs. 1 and 2, with the armature mounted therein;

50 Fig. 6 shows a transverse section taken on the line 6—6 of Fig. 5, showing the manner in which the armature is held in position in the spool; and

Fig. 7 is a circuit diagram illustrating one set 55 of circuit connections which may be employed in

using the amplifier illustrated in Figs. 1, 2 and 4.

As illustrated in the drawings, the improved amplifier comprises a U-shaped permanent magnet 10 formed of steel which has its parallel arms 10^a and 10^b, as viewed in Fig. 2, connected to a pair of U-shaped pole pieces 11 and 12, respectively, interposed between them and formed of magnetizable material such as soft iron. The pole piece 11 comprises a pair of field members or side plates 11^a and 11^b terminating in pole faces 11^c which are opposed to the pole faces 12^c formed on the field members or side plates 12^a and 12^b, respectively, of the opposite pole piece. A pair of plates 13, formed of a phenol condensation product or other hard insulating material, engage the outer sides of the front and rear arms 10^a and 10^b of the magnet 10 and project beyond the upper and lower edges of these arms. These plates are secured together by bolts 14 which have their threaded extremities engaged by nuts 15. The front and rear arms of the magnet 10 are adapted to be drawn together by tightening the nuts 15 for the purpose of regulating the spaced relationship of the pole faces 11^c and 12^c and to clamp together the two parts of the winding spool hereinafter described. The extent to which the arms of the magnet 10 may be thus drawn together is limited by the spacing sleeves 16 which extend between the plates 13 and are engaged by the bolts 14.

The chamber formed by the opposed U-shaped pole pieces 11 and 12 is occupied by a winding spool 18 which is made up of a front half 18^a and a rear upper half 18^b, both formed of molded insulating material, such as Bakelite. The spool 18 has a central passage 19 in which there is mounted the armature 20 which is formed as a flat plate made of magnetizable material such as soft iron. The construction of the spool 18 and the method of mounting the armature 20 therein are illustrated in the United States Letters Patent of Albert Earl Woodruff and Albert Frederick Horlacher, No. 2,241,105, dated May 6, 1941. The hub of the winding spool comprises a front plate 18^c and a rear plate 18^d which are united at their ends with outwardly extending plates or flanges 18^e and 18^f, respectively. These plates 18^e and 18^f fit within the side plates 11^b and 12^b, respectively, of the pole pieces 11 and 12 and they are adapted to have wound around them the insulated wire forming the magnetizing coil 21 which is adapted to be connected in the input circuit over which is received the alternating current of audible frequency to be amplified and in response to which the armature 20 is vibrated.

The front half 18^a of the winding spool 18 is shown particularly in Figs. 5 and 6 where it is illustrated as comprising the plate 18^c and the flanges 18^e, previously referred to, with the plate 18^c cut away longitudinally on its inner side to form a groove or recess 18^g in which is mounted the body portion of the armature 20 having the form of a rectangular plate. As shown in Fig. 6, the rear half 18^b of the spool has its central plate 18^d cut away in a similar manner to form a groove or recess 18^h and the two recesses 18^g and 18^h thus form a chamber in which the intermediate portion of the armature 20 is free to move when the end portions thereof vibrate between the opposite pole faces of the pole pieces 11 and 12, the faces of the grooves or recesses 18^g and 18^h being substantially flush with the pole faces 11^c and 12^c, respectively, when the parts are assembled as shown in Fig. 2.

At the sides of the recess 18^g, the center plate

18^c of the front half of the spool is provided with outwardly extending notches 18ⁱ which communicate with enlarged notches 18^j extending inwardly from the outer lateral edges of the part 18^c. The openings 18ⁱ are adapted to receive and be loosely engaged by outwardly projecting trunnions 20^a which are integrally formed on the armature 20 at its opposite sides and midway between its ends. These trunnions are formed integrally with enlargements 20^b in the form of rectangular heads which fit tightly within the notches 18^j, as shown at the lower side of Fig. 5. After these trunnions 20^a and the head 20^b have been put in place, spring metal clips 22 are placed around the lateral edges of the center plate 18^c of the front part of the spool with the flanges 22^a thereof overlying the heads 20^b of the armature, as shown in the upper part of Fig. 5, and with their other flanges 22^b underlying the center plate 18^c of the spool. These parts 22 very firmly clamp the armature trunnion heads 20^b so that they are securely retained in place and cannot move. The vibration of the armature twists the trunnions 20^a which have sufficient resilience for the purpose. When the parts are thus assembled, as shown in Fig. 6, the edges of the flanges 18^e and 18^f which are formed on the front and rear halves of the spool, respectively, engage each other along surfaces 20^k, thus limiting the extent to which the two halves of the spool may be forced together by the clamping action exerted through the tightening of the nuts 15 on the bolts 14. In this way, a rigid assembly is brought about with the pole pieces and the parts of the spool securely clamped in place between the upper and lower arms of the magnet 10 while at the same time providing a chamber in which the armature 20 is free to vibrate under the influence of the magnetic forces set up through the action of the alternating current passing through the coil 21.

The magnetizable material of which the armature 20 is formed should be somewhat resilient so that the armature will be capable of vibration through the twisting of the trunnions 20^a which connect the body of the armature with the fixed integrally formed heads 20^b. Upon a tilting movement of the armature in either direction from its neutral position, the trunnions 20^a will be put under torsional stress and be twisted so that they will act as springs which tend to return the armature to its neutral position midway between the pole faces, as illustrated in Fig. 2. By suitably proportioning the dimensions of the trunnions 20^a, this spring action may be caused substantially to neutralize the polarizing effect of the permanent magnet 10, within the normal range of the vibratory movement of the armature 20, so that the armature will occupy a "floating" position between the pole pieces and will tend to remain in any position to which it is moved except as it is influenced by the magnetizing forces set up by the current passing through the coil 21.

This balancing effect of the spring action of the trunnions 20^a and the field of the permanent magnet, throughout the normal working range of movement of the armature, is illustrated diagrammatically in Fig. 3 where the abscissa minus X and plus X represent linear movements of the armature ends from a neutral or intermediate position between the pole faces and where the ordinate plus T and minus T represent the torque exerted on the armature. The point 0 represents the neutral or central position of the armature

and the force exerted on the armature by the permanent magnet 10 as the armature moves from that central position is shown by the curve M. The force exerted by the spring action of the trunnions 20^a in various positions of the armature is shown by the straight line S. It will be observed that the curve M is a straight line within a range of movement of the armature between the lines plus F and minus F, indicating a linear variation of the magnetic force according to the distance of the armature from the neutral position, whereas the magnetic force increases very rapidly and at an increasing rate when the armature moves beyond the range indicated by the lines plus F and minus F to positions closer to the pole faces, as shown by the curved extremities of the curve M. Thus, by confining the movement of the armature to the working range indicated by the distance between the lines plus F and minus F, it is possible, by a suitable proportioning of the parts, to cause the spring action of the trunnions 20^a substantially to neutralize the magnetic torque due to the polarization of the permanent magnet 10 in all positions of the armature within this range, so that the armature will remain in any of these positions to which it is moved, when the magnetizing coil 21 is not energized.

In order to confine the movement of the armature within the "linear" range just referred to wherein the magnetic forces exerted through the pole pieces by the permanent magnet 10 will vary uniformly with changes in the position of the armature, as heretofore described, and to prevent the armature from adhering to the pole faces, the pole faces 11^c and 12^c are provided with coatings 23 of non-metallic and non-magnetic material such as paper, yarn or the like which may be cemented or otherwise secured to the pole faces and which may have any desired thickness adapted to confine the movements of the armature within the prescribed range.

The amplifying device should be so mounted that the armature 20 will be located in a vertical plane and this armature is provided at one end with a projecting ear 20^c having an aperture 20^d therethrough to receive a short bolt 24 which secures in place a U-shaped brass clip or contact plate 25, the arms of which embrace the ear 20^c. A nut 26 engages the bolt 24 to secure the clip 25 in place and this clip serves as a non-magnetic contact member for actuating the microphone cells 30 which are disposed on opposite sides thereof without extending the ear 20^c and unbalancing the armature. The cells are arranged with their axes extending horizontally and they are carried by a pair of insulating blocks 31, formed preferably of Bakelite, which are secured to the upper and lower plates 13 by screws 32.

Each cell 30 comprises a metal tube 33 formed of brass or other non-magnetizable metal and having a press fit in a vertical hole 31^a formed in one of the blocks 31. These tubes are internally threaded at their outer ends and these ends are closed by threaded plugs 34. Large washers 34^a are placed over the ends of the tubes 33 and are secured in place by terminal screws 34^b entering threaded holes in the outer ends of the plugs 34 and providing means for making connections with an electric circuit. The tubes 33 project from the blocks 31 toward the contact plate 25 but terminate short of it to a substantial degree so that the plate may move freely between the ends of the tubes. The projecting end of each tube is fitted by a flexible sleeve 35 formed of loosely woven silk cloth. Each cloth

sleeve 35 is spread out at its base to form a flange 35^a seating against the adjacent block 31 and it extends beyond its tube 33 to the face of the contact plate 25 where it is again spread out to form another annular flange 35^b seating against this plate. There is thus formed on each side of the contact plate of the armature a cell chamber 36 made up partly of the bore of a tube 33 and partly of the cloth sleeve and each of these chambers is substantially filled with a quantity of carbon granules 37. To improve the microphonic action of the cells, the metallic parts engaged by the carbon granules, including the contacting surfaces of the plate 25, the internal surfaces of the tubes 33 and the ends of the plugs 34, are preferably gold plated. The carbon granules are adapted to be compressed on one side of the armature contact plate 25, upon movement of the armature, at the same time that the pressure on the granules at the other side of the contact plate is reduced, thus producing a differential action in the circuit of Fig. 7 in which the cells 30 are connected. As vibration of the armature takes place, the flexible cloth sleeves 35 which form the inner ends of the cell chambers readily adjust themselves to the changing position of the contact plate 25. The initial compression of the carbon granules 37 in these cells may be regulated by adjusting the positions of the threaded plugs 34 in the tubes 33.

One method of using the improved amplifier is diagrammatically shown in Fig. 7 which illustrates the magnetizing coil 21 as being connected in an alternating current telephone input circuit

35 over which is received the current of audible frequency to be amplified. Assuming that the arm 10^b is the north pole of the permanent magnet 10, the magnetic field produced in the armature by the alternations of the current in the input circuit acts first to supplement the flux passing from one positive pole piece 12^a and then to supplement that from the other positive pole 12^b, so that the positive poles alternately exert greater attractive forces on the opposite armature ends, thus causing the armature to vibrate about the axis of the trunnions 20^a. During this action, the magnetic flux produced by the current in the coil 21 is, at a given instant, added to a part of that passing from one pole piece 12^a into the armature and this flux passing through the armature enters the negative pole piece 11^b at the other end of the armature; upon reversal of the current in the coil 21, the direction of the field in the armature is reversed and its flux is then added to a part of that passing from the other pole piece 12^b, thus producing a pulsating magnetic field acting on the ends of the armature.

These vibrations of the armature are imparted to the microphone cells 30 which are differentially connected in the direct current circuit 41, as shown in Fig. 7. This circuit includes conductors 42, connecting the terminals of the cells 30 to the terminals of the primary winding of an induction coil 43, and a conductor 44 connected to the contact plate 25 between the two cells and leading through a battery 45 to the middle point of the primary winding. The secondary winding of the induction coil 43 is connected to the output circuit 46.

70 The vibration of the armature 20 actuates the two microphone cells 30 differentially, one rising in resistance as the other falls, and vice versa. The currents in the two parallel conductors 42 tend to neutralize each other in the induction coil and the magnetism in the core of the coil is

due to the difference in the ampere-turns of the two sections of the primary winding of the coil which are connected to these two conductors 42. As the resistance of one microphone cell decreases and its current increases, the resistance of the other microphone cell increases and its current decreases and, since the two parts of the primary winding have the same number of turns, the vibration of the armature causes an alternating magnetism in the core and an alternating voltage in the secondary winding of the induction coil which is connected in the output circuit 46. The output current has the same wave shape as the input current but is very much stronger, thus producing the desired amplification of the input current and making it possible to obtain the desired strength of reproduction of the speech or other sounds transmitted, through the use at the receiving end of the circuit of a suitable sound translating device.

Although one form of the invention has been shown and described by way of illustration, it will be understood that it may be constructed in various other embodiments which come within the scope of the appended claims.

I claim:

1. In an amplifying device, a polarizing magnet, field members of magnetizable material connected to said magnet and having opposite pole faces spaced apart, means for varying the spaced relation of said pole faces, an armature mounted for movement between said pole faces, means secured to said pole faces for confining the vibrations of said armature to a range in which the magnetic attraction thereon varies uniformly with the variation in the distance of the armature from the attracting pole face, means for balancing the magnetic force exerted on said armature by said magnet in different positions of said armature, and means for setting up a pulsating magnetic field in said field members for actuating said armature.

2. In an amplifying device, a polarizing magnet, field members of magnetizable material connected to said magnet and having opposite pole faces spaced apart, an armature mounted for movement between said pole faces, means applied to said pole faces for confining the movement of said armature within a predetermined range in which the magnetic attraction thereon varies uniformly with the variation in the distance of the armature from the attracting pole face, means for balancing the magnetic force exerted on said armature by said magnet in all positions of said armature within said range, and means for setting up a pulsating magnetic field in said field members thereby to actuate said armature.

3. In an amplifying device, a polarizing magnet, field members formed of magnetizable material connected to the opposite end portions of said magnet and having opposed pole faces spaced apart, an armature mounted for movement between said pole faces, resilient means providing the sole support for said armature and acting normally to balance the attractive force of said magnet, a winding adapted to be connected in an alternating current circuit and arranged to set up a pulsating magnetic field in said field members to cause said armature to vibrate between said pole faces, a microphone cell arranged to be actuated by the movement of said armature, and means for confining the vibrations of said armature to a range in which the magnetic attraction thereon varies uniformly with the var-

iation in the distance of the armature from the attracting pole face.

4. In an amplifying device, a polarizing magnet, field members of magnetizable material connected to said magnet and having opposite pole faces spaced apart, an armature positioned between said pole faces and provided with fixed trunnions adapted to be twisted to permit pivotal movement of said armature, said trunnions being adapted by their resilience to balance the attractive force of said polarizing magnet in all positions of said armature within a working range, means for confining the movement of said armature to said working range, and means for setting up a pulsating magnetic field in said field members thereby to actuate said armature.

5. In an amplifying device, a polarizing magnet, field members formed of magnetizable material connected to the opposite ends of said magnet and having opposed pole faces spaced apart, an armature of magnetizable material mounted for movement between said pole faces, an alternating current input circuit including a magnetizing coil surrounding said armature and arranged to set up a pulsating magnetic field in said field members to cause said armature to vibrate between said pole faces, a microphone cell arranged to be actuated by the movement of said armature, and coatings applied to said pole faces to confine said armature to a range of movement throughout which the magnetic attraction thereon varies directly with the distance of the armature from the attracting pole face.

6. In amplifying apparatus, a magnetic device having a winding adapted to be connected in an alternating current circuit and having a vibratory part responsive to fluctuations of said current, a contact member movable with said vibratory part, insulating blocks carried by said device on opposite sides of said contact member, tubes mounted in said blocks and projecting therefrom toward said contact member, sleeves of loosely woven cloth fitted over the inner ends of said tubes and engaging opposite faces of said contact member, particles of carbon occupying said tubes and said sleeves and engaging said contact member, and means for adjusting the normal compression of said particles of carbon.

7. In amplifying apparatus, a magnetic device having a winding adapted to be connected in an alternating current circuit and having a vibratory part responsive to fluctuations of said current, a contact member movable with said vibratory part, insulating blocks carried by said device on opposite sides of said contact member, tubes mounted in said blocks and projecting therefrom toward said contact member, sleeves of loosely woven cloth fitted over the inner ends of said tubes and engaging opposite faces of said contact member, particles of granular conducting material occupying said tubes and said sleeves and engaging said contact member, and plugs adjustably engaging the outer ends of said tubes for regulating the normal compression of said particles.
